UNITED STATES PATENT OFFICE.

HERBERT N. NORTHROP, OF SOMERVILLE, MASSACHUSETTS.

MOISTENER-PAD.

No. 842,108.

Specification of Letters Patent.

Patented Jan. 22, 1907.

Application filed February 5, 1906. Serial No. 299,627.

To all whom it may concern:

Be it known that I, HERBERT N. NORTHROP, a citizen of the United States, residing at the city of Somerville, in the county of 5 Middlesex and State of Massachusetts, have invented a new and useful Improved Moistener-Pad, of which the following is a specification.

This invention relates to a pad for moistening the surface of envelopes preparatory to affixing a postage stamp or stamps thereto or for moistening the adhesive or gummed surface of postage-stamps preparatory to affixing them as desired.

15 In the accompanying drawings, forming a part of this specification, Figure 1 is a side view of the moistener-pad of this invention. Fig. 2 is a plan view. Fig. 3 is a longitudinal vertical section, dotted line 3 3, Fig. 2; and 20 Fig. 4 is a transverse vertical section, dotted line 4 4, Fig. 3.

In the drawings, A represents a chambered block or reservoir, particularly shown as rectangular on all its sides and top and bottom 25 and capable of holding water.

B is a pad of felt, cloth, or other suitable material capable of absorbing and retaining water and disposed upon the top or upper side A² of the water-reservoir A, and which 30 reservoir for holding said pad in place and preventing its lateral or lengthwise movement has an upward-projecting flange a around its top of sufficient height therefor. This pad is in at least two layers, the lower 35 one of which has a strip extension B², leading through an opening A³ of the top A² of the water-reservoir and into the water-chamber thereof and preferably of a length to have a more or less portion of it lie along 40 upon the bottom of the water-reservoir. This extended strip B² of the lower layer of the pad passes through a fixed tube D of the top of the water-reservoir, and this tube extends downwardly into the water-chamber 45 of the reservoir and terminates approximately near the bottom of said chamber, where it opens thereto.

The pad-bed of the reservoir A, and preferably at one corner thereof, has a raised portion E, which extends across the bed for a part

of its width and transversely and for its full length is preferably of convex shape. This raised portion is covered by the pad, and lying over and above it at a short or sufficient distance is a stationary presser-foot or piece F, 55 fixed to the pad-bed, and which is preferably yielding, as also on its under side or face—that is, its side or face toward said raised portion—if said raised portion is convex, as described and shown, is of a concave shape in 60 the same direction therewith to substantially conform with said convexity, and the two, said raised portion and said presser-foot, form a throat or passage G through which to pass or draw or run an envelop to be moistened, and thereby the better to insure proper contact of the envelop with the moistening pad for the moistening of the envelop for the after affixing of a postage stamp or stamps.

A yielding presser-foot permits the passage 70 or drawing or running of the envelopes under it for moistening them of greater or lesser thickness of contents. Again, the tube D enables the water-reservoir not only to be filled with water as may be desired, but also, 75 if the height or depth of water is not above a certain or defined limit, plainly there can be no possibility of the accidental running out of the water from the reservoir should the reservoir be upset in its use.

The water-reservoir, with its top and its tube, may be of glass, india-rubber, or any other suitable material and molded in one piece, in which case the bottom would be properly inserted and secured in place thereafter. Again, the body, with the bottom of the reservoir, may be of one piece and the top or pad-bed located thereon and either left 85 loose or cemented or otherwise secured in place, as may be thought best.

In the use of the moistener-pad of this invention a postage-stamp to be moistened is applied to the pad at any portion of its exposed surface.

Having thus described my invention, what 95 I claim, and desire to secure by Letters Patent, is—

A moistener-pad composed of a water-reservoir, a water absorbent and retaining pad on the top of said water-reservoir in super- 100

imposed layers, one of which has a strip continuous therewith and which enters into said reservoir, in combination with a raised portion of the pad-bed, on and over which a layer of the pad lies, and a spring and yielding presser-foot above said pad fixed at one side or portion and open at all of its other sides or portions, substantially as described.

In witness whereof I have hereunto set my hand in the presence of two subscribing witnesses.

HERBERT N. NORTHROP.
